[57] **CLAIM**

The ornamental design for a combined ceiling fan motor
housing and light, as shown and described.

DESCRIPTION

FIG. 1 is a perspective view thereof;

FIG. 2 is a side view in elevation thereof, the other sides
being identical to that shown;

FIG. 3 is a top plan view thereof, on a reduced scale; and
FIG. 4 is a bottom plan view thereof, on a slightly reduced
scale.

The broken lines shown in the drawing are environmental
only and form no part of the claimed design.
